FEED MECHANISM FOR DRILLING MACHINES AND THE LIKE

Filed Oct. 17, 1929

INVENTOR.
Wilson P. Hunt.
BY Walter N. Haskell.
his ATTORNEY

UNITED STATES PATENT OFFICE

WILSON P. HUNT, OF MOLINE, ILLINOIS, ASSIGNOR TO MOLINE TOOL COMPANY, OF MOLINE, ILLINOIS

FEED MECHANISM FOR DRILLING MACHINES AND THE LIKE

Application filed October 17, 1929. Serial No. 400,232.

My invention has reference to a feed mechanism for drilling machines, and other machines of that character, and relates more specially to means for controlling the movement of the tool or other part, so that it will conform readily to variations in the character of the piece of work that is being operated upon. A similar device is set forth in a former application for Letters Patent of the United States, filed by myself on the thirty-first day of May, 1929, Serial No. 367,330. Said former application included a feed cylinder, for the use of compressed air or similar force for moving the part to be transported, a secondary cylinder containing a non-elastic controlling element, and an additional container, or tank, connected with said secondary cylinder, and permitting a variation in the amount of said controlling element under varying operating conditions. In the present invention one of the cylinders is done away with, and the device considerably simplified.

The operation of the invention is largely similar to that of the machine shown in said former application, the tool being given a relatively rapid movement until the piece of work is encountered thereby, following which there is a more deliberate movement thereof, the tendency of the tool to move faster or slower being imparted to the control element, and receiving a quick response therefrom.

The particular construction, arrangement, and operation of the various parts of the invention will more fully appear from the following specification, taken in connection with the accompanying drawing, showing the invention in elevation, with some of the parts in vertical medial section.

The reference number 1 indicates a cylinder, fitted with an upper end-plate 2, and a lower end-plate 3. In the end-plate 2 is slideable a rod 4, provided at its lower end with a piston 5, having a central packing ring 6, fitting snugly in the inner wall of the cylinder. On the upper end of the rod 4 is a series of teeth 7, in mesh with the teeth of a pinion 8, fixed on a shaft 9, which has a rotatable mounting, not shown in the drawing. The

pinion 8 is also in engagement with the teeth 10 on a bar 11, to the lower end of which is fixed an arm 12, in the other end of which is rotatably supported a spindle 13, to the lower end of which is secured a drill 14. The mechanism by means of which the spindle 13 is rotated is of a well-known type, and is omitted from the drawing. The movement of the rod 4 in either direction operates to move the bar 11 in a contrary direction, to 60 the same degree.

Communicating with the cylinder 1 through the end-plate 3 thereof is a pipe 16, through which an operating fluid or liquid may be introduced under pressure to that part of the cylinder which is beneath the piston 5. The pipe 16 is connected with a supply pipe 17 through a valve casing 18, containing a valve of a common three-way type, under the control of a hand-lever 19. Movement 70 can thereby be imparted to the rod 4 in a direction to cause a downward feed of the rod 11 and drill 14.

Supported at a little height above the cylinder 1 is a tank 20, in communication with the cylinder 1 by means of a pipe 21, one end of which passes through the end-plate 2. Cut in to the pipe 21 is a housing 22, containing a valve chamber 23, the upper end of which communicates with the tank 20 through a pipe 24. One end of the pipe 21 communicates with the tank 20 through a needle-valve fitting at 25. Within the chamber 23 is a valve 27, on the lower end of a rod 28, the upper end of which has a pivotal connection 85 with a cam-lever 29, pivoted at one of its ends to a fixture at 30. Fixed to the rod 4 is an arm 31, carrying a roller 32, adapted for engagement with the edge of the cam 29 and the extension 33 thereof.

The upper part of the cylinder 1, above the piston 5, is designed to contain a quantity of oil or other non-elastic medium, which, upon the upward movement of the piston 5, is forced upwardly into the tank 20. At the 95 beginning of this movement the valve 27 is in the lower part of the chamber 23, permitting a comparatively rapid escape of the liquid through the pipe 24 into the tank. This permits a correspondingly rapid movement of 100

the rod 4 upwardly, and of the rod 11 and tool 14 downwardly until the tool comes in contact with its work, at which time the cam lever 29 is elevated by the arm 31, closing the valve 27 against the outlet to the pipe 24, and turning the flow of oil through the longer branch of the pipe 21. The movement of the oil through this pipe and the fitting 25 is controlled by means of a needle-valve 34, on the lower end of a rod 35, which extends upwardly through the tank 27, and above the same, to a connection with a governor apparatus of a common type, shown at 36. Included in said governor apparatus is a worm drive 37, in mesh with a worm-gear 38 on a shaft 39, said shaft being operatively connected with the shaft 9 by a speed reduction gear train shown generally at A. Any excessive movement of the bar 11 is imparted at once to the governor mechanism, tending to lower the rod 35 and valve 34, and restricting the flow of the liquid through the valve. This valve is normally open to such an extent as to permit a continued movement of the tool after it encounters the work, but at a greatly reduced rate of speed, and in the event of the tool entering a soft spot or pocket in the metal, with a tendency to feed more rapidly, the valve responds at once to this impulse, retarding the flow of the control medium, and keeping the tool at a uniform rate of speed.

During the continued upward movement of the rod 10 the roller 32 is in contact with the extension 33, holding the valve in position to keep the pipe 24 closed. Upon the work of the tool being finished the valve at 18 is turned to permit an exhaust of the air in the lower part of the cylinder 1, and at the same time permit a movement of the operating fluid from the pipe 17 through a pipe 40 to the upper end of the tank 40, tending to force the control medium in said tank back into the cylinder 1, moving the piston therein downwardly, and returning the drill 14 to its original position. This movement is assisted by the weight of the oil in the cylinder 1 and tank 20.

It will be obvious that in the cycle of movements of the machine hereinbefore set forth the tool will approach the work at a rapid rate of speed, which will be reduced and automatically controlled upon the tool coming in contact with the work, and that upon the completion of the special operation of such tool it will be returned at once to position for another operation.

In the operation of drills and similar tools the work is usually supported upon some sort of a base or table, and in cases where it is desired to have the tool held in a stationary position, and the work moved toward or from the same, the present invention can be employed for operating the work-bearing table, and controlling the movements thereof. Changes can also be made in the general con-

struction of the machine and the manner of operating the same, and continue within the scope of the invention.

What I claim, and desire to secure by Letters Patent, is:

1. In combination with a tool organism including a tool to be carried thereby, a cylinder, a piston in said cylinder, a piston-rod for said piston, operatively connected with said tool organism, means for introducing a fluid force on one side of said piston, an auxiliary container in proximity to said cylinder, and united therewith by passages of varying capacity, means for closing the larger of said passages, means carried by said piston-rod for actuating the last-named means at the end of a predetermined movement of said rod, a fluent non-elastic medium contained in said cylinder on the opposite side of the piston from the fluid force, and releasable into said auxiliary container through said passages, and means for controlling the release of said medium automatically from the movement of said tool organism, through the smaller of said passages.

2. In combination with a tool organism including a tool carried thereby, a feed mechanism for said tool organism comprising a cylinder, a piston therein, a rod for said piston operatively connected with said tool organism, means for supplying a fluid elastic force to said cylinder on one side of the piston, an auxiliary compartment in proximity to said cylinder, a pair of conduits connecting said compartment with said cylinder, on the opposite side of the piston from said force, one of said conduits being of a relatively limited capacity, a fluent non-elastic medium in said cylinder, releasable through said conduits into said auxiliary chamber, a valve adapted to close the larger conduit and means for closing the same upon the piston rod reaching a predetermined point in its movement, a valve for the limited conduit, a governor mechanism connected with said last-named valve, for the control thereof, and connections between said governor mechanism and said tool organism, capable of receiving the impulses of said tool organism and imparting the same to the governor mechanism.

3. In combination with a tool organism, a cylinder, a piston therein, a piston-rod for said piston operatively connected with said tool organism, an auxiliary container in proximity to said cylinder, a main conduit connecting said container with said cylinder and valve-chamber therein, a valve in said chamber and rod therefor extending beyond the chamber, a cam-lever connected with said rod, means carried by the piston-rod for actuating said cam-lever, a by-pass from said main conduit to said auxiliary container, a valve in said by-pass and rod therefor, a governor device operatively connected with

said rod, gearing connecting said governor device with said tool organism, and capable of imparting the impulses of said tool organism to the governor device, and means for
5 supplying an operative force to that end of said cylinder opposite to the end communicating with said auxiliary container.

In testimony whereof I affix my signature.
WILSON P. HUNT.
